Specification for Design.

Patented Apr. 18, 1922.

Application filed July 18, 1921. Serial No. 485,764. Term of patent 14 years.

To all whom it may concern:

Be it known that I, JOSEPH HARASYM, formerly a subject of Austria, now a citizen of Ukraine, and now residing at Chicago, county of Cook, and State of Illinois, have invented a new, original, and ornamental Design for a Combined Lamp and Talking-Machine Casing, of which the following is a specification, reference being had to the accompanying drawing, forming a part hereof.

Figure 1 of the drawings is a view in front

elevation of a combined lamp and talking machine casing of my improved design. Figure 2 is a view taken at the line 2—2 on Fig. 1 and viewed in the direction of the arrows; and Figure 3, a section taken at the line 3—3 on Fig. 1 and viewed in the direction of the arrows.

I claim:

The ornamental design for a combined lamp and talking machine casing as shown.

JOSEPH HARASYM.
